UNITED STATES PATENT OFFICE.

JACOB COHN, OF SHEPHERDS BUSH, LONDON, ENGLAND, ASSIGNOR TO NONEX SAFETY TANK SYNDICATE LIMITED, OF LONDON, ENGLAND.

SAFETY VENTING ATTACHMENT.

No. 903,841.

Specification of Letters Patent.

Patented Nov. 17, 1908.

Application filed May 7, 1907. Serial No. 372,428.

To all whom it may concern:

Be it known that I, JACOB COHN, a subject of the German Emperor, residing at 19 Ashchurch Grove, Shepherds Bush, in the county of London, England, have invented certain new and useful Improvements in Safety Venting Attachments; and I do hereby declare the following to be a full, clear, and exact description of the invention, such 10 as will enable others skilled in the art to which it appertains to make and use the same.

This invention relates to safety devices for venting casks, cans and other vessels in such a way that the accidental explosion of their 15 liquid contents, when of an inflammable nature, is efficiently prevented.

The device is of the type in which a cylinder or a plurality of cylinders of wire gauze, protected, if desired, by cylinders of 20 perforated metal, are mounted in connection with the opening in the vessel, say, the bung hole in the case of a cask, in such a way that when the bung hole is open if the liquid should become fired the fire will be unable to 25 pass through the gauze or other cylinder and ignite the whole of the liquid. With apparatus of this class as hitherto constructed it has been proposed to provide the screw cap or other device by means of which access is obtained 30 to the bung hole, for filling and other purposes, with a fusible plug secured to its seat by means of soft solder, which plug on a rise in temperature is blown out of the cap or the like and prevents explosion. I have 35 found this expedient objectionable in practice owing to the uncertainty of temperature or pressure necessary for releasing the plug, and owing to the possibility of the plug becoming damaged by an accidental blow or 40 otherwise in the event, say, of a cask falling over.

According to a former invention of my own for which I have obtained Letters Patent No. 840,992 dated January 8th, 1907, I 45 have already provided for the large and permanently fixed tanks, a venting device resting by means of gravity in its seating and automatically releasing the confined gases when their pressure is sufficient to overcome 50 the weight of the seated valve, but this arrangement while answering admirably for the purpose for which it was intended is not suitable for barrels and other receptacles in transit from place to place or in vehicles in 55 the case of which it is not desirable to use a

valve held on its seating by the force of gravity alone.

My present invention refers to a valve for automatically releasing the pressure when it reaches any given point and is applicable to 60 all classes of venting devices of the character before mentioned. And in order that my said invention may be better understood I will proceed to describe the same with reference to the drawings accompanying this specification, in which my invention is shown applied to two forms of safety venting devices, located in the bung hole or filling hole of a cask, tank or the like, and in which— 65

Figure 1, is a vertical sectional view of one 70 form, and Fig. 2, a like view of another form of my invention.

As shows, for example, a cylinder of wire gauze of suitable mesh; the particular construction of the cylinder forming no material part of my invention. This cylinder is soldered or suitably fixed to the lower part of a tubular piece *b*. In the form of the device shown in Fig. 1, the tube is beveled to form a counter furnished with a boss or projection *b'* and its bore is beveled at its upper end to form a seat for the cap *e* as shown. Surrounding the tube *b* is another tube *c* provided with a screw threaded extension at its upper end to receive the cap, and also 80 having its inner upper end beveled to receive the boss *b'*. The tube *c* is further provided with a flange *d* for attachment by screws, or other suitable means, to the wall of the vessel surrounding the bung hole and 85 containing the inflammable liquid. 90

e is a cap which screws on to the outside of the tube *c*. This cap *e* has a circular depression *f* countersunk in the middle thereof and a central hole *g*, extending from the bottom 95 of the countersunk depression to the other side of the cap *e* in which is screwed or otherwise secured a valve seating *u*.

h is a guide piece fixed at the bottom of the seating *u*, the guide piece in this particular case assuming the form of a ring with a number of arms so that air or gas can pass up around the ring past the guide piece.

In the top of the cap *e* is fitted a valve which comprises the valve proper *j* consisting in this case of a perforated hollow disk having the beveled portion *j'*, and which disk is of sufficiently small size to enable it to rest on the bottom of the depression *f* on the seating *u*. This disk *j* has a packing ring *j''* on its under 110

side, as shown, in order to make a tight joint, and a circular perforated upstanding portion *k* into which a rod *m* provided with a ball *n* at the top, can be dropped, the hole 5 being so shaped that the ball cannot drop through. When inserted through the upper perforation in the valve *j* the ball may be retained in position by means of a screw or other cap *p*. The rod *m* passes through the 10 guide *h* and a helical spring *q* is placed around the rod *m*, between the guide *h* and a nut or the like screwing on to the end of the rod *m*.

The construction of the valve at Fig. 2 is 15 similar to that shown at Fig. 1, but in this case an air hole *s* is shown which allows air to pass through the cap *p* and find access to the inside of the vessel so as to facilitate the egress of liquid when necessary, through, a 20 spigot or other device, not shown, which may be provided on the barrel. In this form of my invention the ball *n* does not fit the hole *k* tight enough to prevent the air from slowly escaping past the same, and the gauze cylinder is attached directly to a tube *t* in the 25 manhole of the cask or the like.

The action of the device will be readily understood: The spring *q* can be regulated to allow the valve to open at any predetermined 30 pressure and when such pressure is reached in the vessel, the inflammable gases or the like open the valve and blow off until the pressure is automatically reduced. In the event of the gases firing, the fire can at the 35 most only pass into the interior of the gauze tube *a* and will not in any event fire the body of the liquid in the vessel. Owing to the way in which the valve is formed, in the event of one side of the cap *j* being fixed by 40 the cask or the like leaning against any obstruction or from any other cause, the valve is still enabled to rise on one side as shown clearly at Fig. 2.

What I claim and desire to secure by Letters Patent of the United States of America 45 is:—

1. In a safety venting attachment for bungs, the combination of a tube *c* provided with an extension at its upper end, said tube 50 adapted to enter the bung hole of a barrel and provided with a beveled inner bore, a tube *b* in said tube *c*, and provided with boss *b'* seating against the bevel in the tube *c*, a wire gauze cylinder *a*, attached to said 55 tube *b*, a cap *e*, fitting the extension on said tube *c*, and provided with a depression *f*, and a central hole *g*, a valve seat *u* secured in said hole, and provided with the guide piece

h, a valve *j* seated on said valve seat, a rod *m* 60 passing through said guide piece, and into said valve, and provided with the ball *n* at its upper end, and a spring *q* surrounding the lower end of said rod, substantially as described.

2. In a safety venting attachment for bungs, the combination of a tube *c* provided with a screw threaded extension at its upper end adapted to receive a cap, and with a flange adapted to secure the same to a barrel, the bore of said tube being beveled at its 70 upper end, a tube *b*, provided with boss *b'*, seating against said bevel, and, also, having its bore beveled at its upper end, a wire gauze cylinder attached to said tube *b*, and located inside said tube *c*, a screw threaded 75 cap *e* fitting the said extension and provided with a depression *f*, the outer walls of which fit the said bevel in the upper end of the bore of said tube *b*, said cap, also, provided with a screw threaded hole *g*, a screw threaded 80 valve seat *u*, fitted in said hole, a hollow valve disk *j*, seated in said depression *f*, and on said valve seat *u*, said valve provided with a hole through its lower wall, and said valve seat provided with a perforated guide *h*, a 85 rod *m* provided with a ball *n* at its upper end, passing through the lower wall of said valve and said guide piece, and a spring *q* surrounding the lower end of said rod and resting at its upper end against said guide piece, 90 substantially as described.

3. In a safety venting attachment for bungs the combination of a tube provided with a screw threaded extension, and a flange adapted to secure the same to a barrel, 95 a cap fitting said extension and provided with a depression, said cap, also, provided with a screw threaded hole, a screw threaded valve seat, fitted in said hole, a hollow valve disk seated in said depression, and on said 100 valve seat, said valve provided with a hole through its lower wall, and said valve seat provided with a perforated guide *h*, a rod provided with a ball at its upper end, passing through the lower wall of said valve and said perforated guide, and a spring surrounding the lower end of said rod and resting at its upper end against said guide, 105 substantially as described.

In testimony whereof, I affix my signature, 110 in presence of two witnesses.

JACOB COHN.
